UNITED STATES PATENT OFFICE.

OSCAR GUGLIELMONE, OF NEW YORK, N. Y.

SNOW-REMOVER.

1,173,956.

Specification of Letters Patent.

Patented Feb. 29, 1916.

Application filed July 25, 1914. Serial No. 853,097.

To all whom it may concern:

Be it known that I, OSCAR GUGLIELMONE, a citizen of the United States, residing at Bronx, in the county of Bronx and State 5 of New York, have invented certain new and useful Improvements in Snow-Removers; and I do hereby declare the following to be a full, clear, and exact description of the invention, such as will enable others skilled in the art to which it appertains to 10 make and use the same.

My invention relates to new and useful improvements in devices for removing snow from railway tracks and resides in the 15 provision of a snow remover that is capable of being readily attached and detached relative to a car, is particularly designed for use in connection with street railways and which will operate in a reliable and expeditious 20 manner to melt and scrape the snow from the tracks.

Another object is to provide a device of the character described which is of simple construction, reliable and efficient in operation, arranged so that it may be readily 25 moved into an out of the way position when not in use and which is inexpensive to manufacture and maintain in operation.

Another and more specific object is to 30 provide a snow remover which comprises track shoes that are so mounted upon the car that they may be moved into and out of operative position and of such construction as to engage within the groove in street rails 35 and melt as well as scrape the snow from the rails.

The above and additional objects are accomplished by such means as are illustrated 40 in the accompanying drawings, described in the following specification and then more particularly pointed out as claimed.

With reference to the drawings, wherein I have illustrated the preferred embodiment 45 of my invention as it is reduced to practice, and throughout the several views of which similar reference numerals designate corresponding parts—

Figure 1 is a side elevation of a street 50 railway car showing my snow remover attached thereto and as it would appear when ready for use, Fig. 2 is a front elevation of my improved device showing a portion of the car to which it is attached and the rails in cross section, Fig. 3 is a vertical sectional 55 view taken through one side of the snow remover, Fig. 4 is a side elevation, and Fig.

5 is a horizontal sectional view taken through the block 8 at a point adjacent its upper end.

Referring to the drawings by characters of reference, A designates the rails of a 60 track and B the street railway car mounted on said rails. One of my improved snow removing devices is mounted at each end of the car preferably.

My improved snow remover consists of 65 identical track engaging shoes 1 and 2 that are arranged to coöperate with the rails A of the track and supported by suitable frame work underneath the car B as will be later more fully described. Each of the shoes 70 consists of an angular metallic body portion 3 that is recessed at its inner end as at 4 so that ready access may be had to a compartment or recess 5 formed adjacent the other end of the body and which receives an 75 electrical heating element 6.

The lower end of the body 3 is reduced 80 and offset slightly or disposed angularly so as to provide a track groove engaging member 7. Secured rigidly by suitable fastening 85 elements to the upper end of each of the body portions 3 is a connecting block 8 that is hinged as at 9 at its upper end to a pivot block 10. The pivot block 10 is pivotally connected with a supporting bar 11 adjacent 85 to one end of said supporting bar by means of a pivot pin 12. The pivot pin 12 is inserted through the supporting bar 11 and a concavo-convex securing plate 13 through the central part of said plate and an opening 14 in said block 10. The pin 12 is loosely mounted in the block 10 and plate 13 and secured to the block 10 by means of the fastening element 15.

The bar 11 extends entirely across the 95 underneath part of the car and supports the shoes 1 and 2 and coöperating parts thereof at its ends. An upper supporting bar 16 of similar construction to the one 11 is secured by upwardly extending bracket arms 17 to 100 and depend from the bottom of the car. This bar 16 is normally spaced from the one 11 but is operatively connected therewith by a number of bowed leaf springs 18 that are similar to the ordinary vehicle 105 spring and interposed between and connected with the opposed faces of the bars 11 and 16. Slotted upstanding guide plates 19 are secured to the lower supporting bar 11 and at one end rigidly and slidably receive buttons or other suitable fastening elements 20 carried on the upper supporting bar 16. The

buttons 20 are slidable within the slotted parts of said plates 19. These plates 19 serve to securely hold the bars 16 and 11 in coöperative relation. The hinges 9 are so arranged that when the shoes are not to be used they may be swung into horizontal or approximately upright position so as to be out of the way.

Brace rods 21 and 22 are arranged between 10 and secured to the block 8 and body 3 respectively of the shoes 1 and 2 and each rod comprises a plurality of sections joined by a universal joint as at 23. These rods 21 and 22 serve to hold the shoes 1 and 2 in proper relation to one another and so that 15 the tracks will be freed from snow.

Secured to the supporting bar 11 adjacent to each and at points spaced from one another are hooks 24 which hooks are arranged 20 to engage the lower edge of the concavo-convex attaching plates 13 and in such manner that said plates 13 are free to rotate. These hooks 24 securely hold the blocks 10 to the supporting bar 11. The attaching 25 plates 13 are interposed between the blocks 10 and 11 and secured rigidly with the blocks 10.

Mounted on either side of the car B are downwardly and outwardly extending bracing arms 25 which at their outer ends are concaved as at 26. These concaved outer end faces are designed to receive the opposed convex faces 27 on the blocks 8 and 10. These arms 25 hold the shoes 1 and 2 rigidly 35 in position in preventing possibility of rearward movement thereof caused by engagement with some obstruction in or on the rails.

A rod 28 is secured at its ends to the opposed faces of the body portions 3 on the members 1 and 2 and consist of three sections that are pivotally connected with each other as at 29. Locking sleeves 29' are slidable on the rod 28 and are designed to be 40 positioned over the pivots 29 so that the sections of the rod 28 are rigidly held against relative movement. A flexible element 30 is secured at its ends at points on either side of the center of said rod 28 and provides a 45 loop to which is secured a chain or other suitable flexible element 31. The flexible element 31 extends upwardly through the car over a guide roller or wheel 32 and is provided with a hook member 33 at its 50 upper end and which is to be connected with a suitable ring not shown so as to support the flexible element within the car and shoes 1 and 2 in up or down position. By communicating a pull to the flexible element 31 55 the shoes 1 and 2 may be raised into approximately horizontal or upright position as they swing on the hinge 9. The heating element 6 is connected with a suitable source of current not shown, by means of 60 conducting wires 34 which extend upwardly 65

through the body 3 and a conduit or passage 35 formed in the block 8 and out through an opening adjacent to the upper end of said passage.

In operation when it is desired to remove 70 snow from the rails A the shoes 1 and 2 are lowered through the medium of the flexible element 31 into position as shown in Fig. 4 and so that the groove engaging portion 7 of the body 3 is within the groove 75 and the under face of the body adjacent to said point slidably engages the tread surface of the rails. The weight of the shoes serves to hold the portion 7 and body of the shoe in proper engagement with the rails. The 80 heating element 6 is then operated so that the points 7 will become heated and the melting of the snow in the groove on the rail and upon the rail is thus provided. The engagement of the body 3 of each of the 85 members 1 and 2 with the rails serves to provide a scraping action as well as removal by melting. The arms 25 have the concaved faces 26 therein formed so that shoulders 36 are provided, said shoulders being arranged in spaced relation to the opposed shoulders formed by the arrangement of the concaved faces 27 on the blocks 8 and 10 and thus it will be seen that the shoes are 90 permitted lateral movement relative to the arms 25. This relative movement is desired when the car is rounding a curve thus the shoes are permitted to remain in position 95 upon the rails.

It will thus be seen that a street car 100 equipped with my improved snow removing devices will not be impeded in its progress by heavy snows as a thorough and efficient removal of the snow from the grooves 105 in the rails and the rail treads is had.

In practice, I have found that the form of my invention, illustrated in the drawings and referred to in the above description, as the preferred embodiment, is the most efficient and practical; yet realizing that the 110 conditions concurrent with the adoption of my device will necessarily vary, I desire to emphasize the fact that various minor changes in details of construction, proportion and arrangement of parts may be resorted to when required, without sacrificing 115 any of the advantages of my invention, as set forth.

What is claimed is:—

1. A snow remover for railway cars, comprising transverse supporting bars secured to the underside of a car, springs secured to said bars, a block supporting bar secured to said springs, blocks secured to said transverse supporting bar, guides secured to the 125 block supporting bars and provided with slots in the ends thereof adapted to receive buttons carried by said transverse supporting bars to allow vertical movement of said block supporting bar in relation with the 130

transverse supporting bar, shoe supporting blocks secured to the block supporting bar, rail engaging shoes secured to said blocks, means for heating said shoes and means for 5 raising and lowering said shoes into and out of engagement with a rail of a railroad.

2. A snow remover for railway cars comprising a transversely supporting bar secured to a car, a block supporting bar mov- 10 ably secured to said transverse supporting bar, concavo convex plates rotatably secured to said block supporting bar, blocks secured to said block supporting bar and adapted to bear upon the concavo convex plates, con- 15 necting blocks hinged to said blocks, rail engaging shoes secured to the connecting block, means for holding said shoes in spaced relation to each other, means for heating said shoes, and means for raising 20 and lowering said shoes into and out of engagement with the rails of a railroad.

3. A snow remover for railway cars comprising a transverse supporting bar, a block supporting bar secured to the transverse 25 supporting bar, means for allowing vertical movement of the block supporting bar in relation to said transverse supporting bar, blocks secured to said block supporting bar, concavo convex plates secured to the block 30 supporting bar between the blocks, hooks secured to said block supporting bar and adapted to engage the periphery of said plates connecting blocks hinged to said blocks, rail engaging shoes formed on said 35 connecting blocks, means for heating said shoes, means for holding said shoes in spaced relation to each other and means for preventing rearward movement of the shoes when in an operative position.

40 4. A snow remover for railway cars comprising a block supporting bar, means for securing said block supporting bar to a car, blocks secured to said block supporting bar, connecting blocks hinged to said blocks and 45 adapted to swing upwardly therefrom, said connecting blocks provided with a passage therein, an angular metallic body portion formed on said connecting blocks and pro- vided with an opening in the rear face there-

of, the lower end of said body portion dis- 50 posed angularly to form track grooved en- gaging members, said angular body portion provided with a recess adjacent the open- ing in the rear wall thereof, an electric heat- 55 ing element mounted in said recess and adapted to pass through the opening and into the passage of said connecting blocks for heating the angular body portion so as to melt ice and snow from a rail, means for holding said angular body portion in spaced 60 relation to another body portion, and means for preventing rearward movement of the track engaging members when in an opera- tive position.

5. A snow remover for railway cars com- 65 prising a block supporting bar, means for securing said block supporting bar to a car, blocks secured to each end of said block supporting bar, connecting blocks hinged to 70 said block, a rail engaging shoe secured to said connecting block, a brace secured to the underside of a car and extending down- wardly into engagement with said blocks and connecting blocks to prevent the rear movement of the shoe when in an operative 75 position, and means for holding said shoes in spaced relation to each other.

6. A snow remover for railway cars com- 80 prising a block supporting bar, means for securing said block supporting bar to a car, blocks secured to said block supporting bar, connecting blocks hinged to said blocks and adapted to swing upwardly therefrom, rail 85 engaging shoes formed on the lower ends of said connecting blocks, horizontally connect- ing bars secured to the shoes to prevent said shoes from moving in relation to each other when in engagement with the railroad rails, and means for preventing rearward move- 90 ment of said shoes when in an operative position.

In testimony whereof I affix my signature in presence of two witnesses.

OSCAR GUGLIELMONE.
